(57) **CLAIM**

The ornamental design for a foot file, as shown and described.

DESCRIPTION

FIG. 1 is a top, front, left side perspective view of a foot file according to my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The long dash-short dash broken lines represent boundaries of the claimed design and form no part of the claimed design. The evenly spaced broken lines depict portions of the foot file and form no part of the claimed design.
